UNITED STATES PATENT OFFICE.

VALERIAN GILLAR, OF VIENNA, AUSTRIA.

IRON-FRAME WINDOW.

Application filed January 25, 1928, Serial No. 249,333, and in Austria June 7, 1926.

This invention relates to improvements in double glazed iron-frame windows and has for its object to improve the construction thereof for attaining in spite of the 5 comparatively simple manufacture, a sufficient tightness of the joints and insulation by avoiding condensing water. According to the invention any water which may have penetrated is led away and the 10 inner sides of the window-panes can be cleaned comfortably.

An inwardly opening double window is illustrated by way of example on the accompanying sheets of drawings in which, 15 Fig. 1 is an inside view of the window constructed according to the invention.

Fig. 2 is a sectional side view on an enlarged scale.

Figs. 3 and 4 show in section the arrangement for closing the openings, which connect the space between the window with the outside air.

Figs. 5 and 6 show the disposition of this arrangement in the lid of cleaning 25 openings in elevation and section respectively.

Fig. 7 illustrates diagrammatically the introduction of cleaning devices into a window-wing.

The profile iron 1 forming the window frame is essentially U-shaped (Fig. 2) and its web is provided with two projecting corners, which form rabbets for the insertion of panes 2 and 3. The profile iron is 35 furnished with two flanges 5 and 6, which are of different lengths and in the shut condition of the window cooperate with and rest on flanges 7 and 8 of profile iron 9, forming the sash frame and thus provide 40 for a tight fit at the inside and outside. The profile iron 9 of the sash frame is essentially Z-shaped and near the flange 8 extends at an acute angle 10 into the wall 11, against which it rests by means of the 45 flanges and a rim 12 extending at a right angle with respect to the flange 8.

The angle-piece 10 of the sash frame, extending into the wall forms a channel, passing right around and collecting rain-water, which may have forcibly entered. 50 The water entered at the sides of the sash frame flows into the horizontally disposed channel of its bottom part comprising small discharge-pipes 14 (Fig. 2), through which 55 flows off the water. The peculiar shape or profile of the sash frame provides for a

tight and firm connection with the wall, without the necessity of employing claws and rolls.

Caps 15 (Fig. 2) are screwed into the horizontally disposed webs of the profile irons forming the window frame, the said caps being provided with holes for the passage of air and connect the space between the window-panes and the window gap, 60 thus with the air at the outside. Each cap consists of a cylindric member 16 (Figs. 3 and 4), provided with an opening 17 in its middle part, and a screw-bolt 18 furnished with a central bore 19 is screwed 65 partly into the open end of the said cylindric member. The inner end of each bore 17 or 19 is conically enlarged and thus forms a seat for a small ball 20. Therefore in both positions, shown in Figs. 3 and 4, the 70 cap can be screwed into the profile iron by means of the screw-bolt 18 or it is possible to arrange the caps in such a manner, that they are invisible as shown in Fig. 2. 75 Another thin cap 21, provided with a hole 21', is pushed onto the cap 16 and may serve for securing a piece of felt, for instance a disc consisting of felt or the like and resting on the outer surface of the bottom of the cap 16. 80

The balls 20, consisting of a light material and fitting well to their seats, provide for a sufficient tight closure of the space between the window-panes. The enclosed 85 air is not subjected to any change provided that its temperature rests the same.

However in case of any change of temperature a compensation takes place in consequence of the relative change of pressure.

If the enclosed unmoved air is heated, for 90 instance owing to the influence of the sun or by an excessive heating of the room, the over-pressure caused by the expansion of the enclosed air, will lift the ball of the top cap and the air which is over is discharged 100 until the pressure becomes equal to that of the outside air, when the ball drops onto its seat and again closes up air-tight. Thereby also the moisture is led off together with the surplus air, so that condensation cannot take 105 place.

However if the enclosed air cools off, a pressure below atmospheric arises in the space between the panes, so that the cold air from outside enters through the bottom cap 110 until the pressures at the inside and outside are balanced. The specific contents of mois-

ture of the enclosed air is reduced by the admission of cold and dry air, so that condensation cannot take place.

In spite of the communication openings 5 with the atmosphere the enclosed air is continuously maintained at the mean temperature between the temperatures at the outside and in the room, because only the small air-currents can take place, which balance the 10 pressures. Therefore the arrangement provides for an efficient insulation, prevents the formation of condensing water and thus fully satisfies both requirements. The arrangement according to the invention avoids 15 the drawbacks of the known communication openings between the interior of the window and the atmosphere, which consist in that the temperature of the air within the window is reduced practically to the outside 20 temperature owing to continuous air-circulation thus producing no insulation, but condensing water.

In order to facilitate the cleaning of the 25 inside of the window-panes, the caps 15 may be screwed into the covers 22 of longitudinal openings, provided in the middle of the profile irons which openings permit the insertion of cleaning tools 23 (Fig. 7). The 30 cover 22, which fits exactly into the opening, is connected by means of rivets 24 with a slightly larger tightening rubber plate 25 and a sheet metal plate 26, both perforated

for the passage of the bolt 18. The cover is secured in the closed position by rotatable bolts 27. All places of the window can be 35 cleaned using the top and bottom openings of each window-frame.

Having now particularly described and ascertained the nature of my said invention and in what manner the same is to be performed, I declare that what I claim is—

1. Double glazed iron-frame window provided with openings in the window frame for establishing communication between the space enclosed by the window-panes and the 45 open air, in which a number of openings are provided, which can be closed in such a manner, that the air can enter at one hole or a group of holes only and leave at the other hole or group of holes only. 50

2. Double glazed iron-frame window in which the window frames are provided, at the top and bottom between the rabbets of the panes with cleaning openings, said openings being capable of being closed by lids 55 comprising means for circulation of the air.

3. Double glazed iron-frame window as claimed in claim 2 in which the lids consist of a plate fitting into the opening and of a larger tightening plate firmly connected 60 with the plate first mentioned.

In testimony whereof I have signed my name to this specification.

VALERIAN GILLAR.
